(57) **CLAIM**

The ornamental design for a base member for a lace tightening device substantially as shown and described.

DESCRIPTION

FIG. 1.1 is a perspective view of the base member for a lace tightening device;

FIG. 1.2 is a back view of the base member for a lace tightening device;

FIG. 1.3 is a front view of the base member for a lace tightening device;

FIG. 1.4 is a first side view of the base member for a lace tightening device;

FIG. 1.5 is a second side view of the base member for a lace tightening device;

FIG. 1.6 is a top view of the base member for a lace tightening device;

FIG. 1.7 is a bottom view of the base member for a lace tightening device.

The portions of the base member for a lace tightening device shown in broken lines form no part of the claimed design.
